DESIGN FOR A LENS FOR AUTOMOBILE LAMPS

Marvin C. Anderson, Spokane, Wash.

Application October 19, 1940, Serial No. 95,934

Term of patent 7 years

To all whom it may concern:

Be it known that I, Marvin C. Anderson, a citizen of the United States, residing at Spokane, county of Spokane and State of Washington, have invented a new, original, and ornamental Design for a Lens for Automobile Lamps, of which the following is a specification, reference being had in the accompanying drawing, forming a part thereof.

Figure 1 is a plan view of a lens showing my new design.

Figure 2 is a side elevational view thereof.

Figure 3 is a cross sectional view of the same taken on the line 3—3 of Figure 1.

I claim:

The ornamental design for a lens for automobile lamps, as shown.

MARVIN C. ANDERSON,
